NICOLAI GRIBOJEDOFF, OF PUTNEY, LONDON, ENGLAND

WINDING MACHINE

Application filed November 18, 1929, Serial No. 405,034, and in Great Britain May 23, 1929.

This invention relates to winding machines for such purposes as the production of cross wound bobbins, taper or bottle shaped bobbins, cop bobbins and the like and has for its object to provide improvements in thread winding machines, such improvements being directed to increasing the winding capacity and also to increasing the speed and the tautness of winding.

Hitherto in machines of the character described the tension capable of being supported by any given thread is that expressed by the length between the tensioning device and the point at which the thread reaches the bobbin or the like which is being wound, which may be a length of 2, 3, 4 or even 6 inches. The tension supportable over such a length is the resultant of the following factors

(a) Staple strength.
(b) Staple length,
(c) Degree of twist, of which for this purpose (a) and (c) may be assumed to be constant and (b) variable.

The present invention consists in a thread tensioning and guiding device wherein the thread passes in series around a plurality of rollers the end roller of which is so disposed relatively to the surface being wound as to be a distance therefrom less than the staple or fibre length in order that the tension used for winding may bear a direct relation to the ultimate tensile strength of the fibre and to exceed that of the thread over any given length.

Reference will now be made to the accompanying drawings which illustrate by way of example a construction according to the invention and in which:—

Figure 1 is an elevation of the thread tensioning and guiding mechanism,

Figure 2 is a partial plan of the tensioning and guiding device shown in Figure 1 on an enlarged scale,

Figure 3 is a sectional plan of a clutch employed for intermittently moving the thread tensioning and guiding device longitudinally of a cop or the like as the latter is wound,

Figures 4, 5, 6 and 7 are detail views of the thread tensioning and guiding device.

In the arrangement illustrated in Figure 1, the invention is shown as applied to a thread winding machine of one character, but it is to be understood that its use is in no way limited in this respect. The thread tensioning and guiding devices 28 are carried by screw threaded portions 27 of vertical shafts 26 around which the tensioning and guiding devices pivot and along which they travel as the thread is applied to a cop spindle 21. One of these thread twisting and guiding devices is illustrated in detail in Figures 4 to 7 and consists of a stationary member 29 carrying a series of rollers 30 and a movable member 31 also carrying rollers 32, the movable member being pivoted around a boss 33 carried by the stationary member 29 and surrounding the shaft 26. The rollers 30 and 32 are of conical or tapered form whilst the outermost roller 34 of each tensioning and guiding device, that is to say, the roller remote from the shaft 26 is not of conical shape and is formed with a groove 35, this roller being driven by frictional contact with the rotating bobbin or cop, and being so close to the surface being wound that the length of thread extending at any time between the groove 35 of the roller 34 and the surface being wound is never greater than one-quarter of the length of fibre in the thread, thus enabling a greater tension to be placed on the thread as it is wound than in the ordinary arrangement wherein a relatively great length of thread extends between a thread guide and an article being wound. Since the winding tension is made to exceed the strength of the thread, tighter winding is obtained, thus making it possible to wind a greater length of thread on each spindle and consequently increasing the winding capacity of a machine having a given number of spindles.

As will be clear from the drawings the thread 36 is passed alternately between the rollers of the members 29 and 31 when the members are in their open position as shown in Figure 4. The movable member 31 is then closed against the member 29 with the result that the rollers 32 take up positions between the rollers 30 and cause the thread to

take the course indicated by the broken lines 36 in Figure 5. The thread, when drawn through the twisting device above described, is also subjected to rotation. The thread is moved sideways in one direction by the rotation of the conical rollers 32 carried by the movable members 31 and is at the same time rotated by the rollers 30 carried by the stationary members 29. According to the conicity of the rollers and the pressure exerted on the thread by the rollers 30 and 32 a more or less twist will be imparted to the thread and, as the thread approaches the last roller in the series, the twist on the thread increases.

This will be more clearly understood by reference to Figure 7, which is an end view of two of the rollers, the thread being shown in sections, and wherein the thread 36 is indicated as being moved by rotation of the roller 30 in the direction of the arrow 37, the thread being thereafter turned in the direction of the arrow 38 and by the next succeeding roller in the direction of the arrow 39. The degree of twist imparted to the thread and consequently the resistance of the thread to breakage is increased by its passage through the coned rollers. The thread is drawn through the device by the rotation of the spindle being wound and the high tension used for winding is not produced until the thread passes from the grooved roller 34 on to the surface of the article being wound. The roller 34 being driven from the bobbin or the like will rotate at the same surface speed but the thread having to pass around a groove of smaller diameter than the roller 34 will be subjected to a retardation which applies the final tension in being drawn onto the article being wound whose surface speed is greater than the surface speed of the interior of the groove. The degree of twist depends on the conicity of the rollers 30 and 32 and also on the initial pressure imparted.

Each screw threaded shaft 26 is carried between members 41 forming fixed parts of the machine framework 42, each shaft being rotatable under the conditions hereinafter described. The boss 33 is internally screw threaded to engage with the screw threaded portion 27 of the shaft 26. As the roller 34 is always pressed by the tension of the thread and a spring disposed in the boss 33 against the cap or the like being wound, the thread guiding and tensioning device 28 makes a swinging movement about the shaft 26.

As the lower part of the section of the bobbin which is being wound acquires a pre-determined diameter it is necessary to raise the thread guiding and tensioning device 28 to a slightly higher level. This is achieved by the following mechanism:—

65 In the framework 42 (see Figure 3) sur-

rounding a part of the length of the shaft 26 two adjustable bolts 43 and 44 are mounted, which bolts act as stops for a pawl 45 pivotally mounted on a lever 46 carried freely by the shaft 26 the said pawl being pressed by a spring 47 into engagement with a ratchet wheel 48 fixed to the shaft 26. With this arrangement the thread guiding and tensioning device moves pivotally about the axis of the shaft 26 as the bobbin is vertically reciprocated. When winding from the top of the bobbin towards the base the guiding and tensioning device and the boss 33 are turned in a clockwise direction by engagement therewith of the ascending bobbin. The boss 33 is frictionally held in engagement with the screw threaded shaft 26, so that the boss grips the spindle sufficiently closely to ensure the spindle normally turning with the boss. As, however, the lower portion of a bobbin becomes fully wound, the amplitude of the pivotal movement of the boss and shaft is such that the pawl 45 is brought into engagement with the stop 43 and the rotary movement of the shaft 26 is stopped so that continued movement of the boss 33 causes it to be fed upwards along the shaft. On the reverse movement, that is when winding from the bottom to the top of the bobbin, the shaft 26 and ratchet wheel 48 move in an anti-clockwise direction (Figure 3) so that the pawl 45 engages the stop 44 and the shaft is held against rotation until the tension and guiding device again engages the lower portion of the bobbin.

By screwing the bolts 43 and 44 into and out of the framework 42 and securing them in adjusted position by means of nuts 49 the winding may be regulated to the desired thickness. If the pawl 45 with the ratchet wheel 48 be likewise made to slide and, if instead of the stops 43 and 44 two curved surfaces be attached to the casing 42, bobbins of different and any desired form (such as oval or spherical) may be obtained. In this case the screw-threaded shaft 26 is stationary and the boss 33 rotates on the shaft 26 or on an extended bush on the ratchet wheel 48.

To effect the results above described, the speed at which the thread is fed through the tensioning device is less than the speed at which it is wound this being achieved by making variable the resistance to rotation of the thread guide rollers 30 and 32, which thus act as thread speed regulators. In the present instance the bobbin spindle is the driving member as far as the thread is concerned and the thread is fed through the guiding device 28 by being drawn therethrough by the rotation of the bobbin spindle 21.

I claim:—

1. A thread winding machine, including a thread tensioning device comprising two piv-

totally mounted elements, a series of conical rollers disposed on each of said elements, the rollers of one series being disposed in opposition to the rollers of the other series, a roller carried by one of said elements remote from the pivot of the latter, said roller having a peripheral groove through which the thread passes when leaving said device.

2. A thread winding machine according to claim 1 wherein the peripherally-grooved roller bears against the body being wound, and including a vertical support on which the thread tensioning device is pivotally mounted and means automatically operated by the body being wound, when said body reaches a predetermined diameter, to raise the thread tensioning device on said support and secure it temporarily in the adjusted position.

20 3. A thread winding machine including a shaft, a thread tensioning device mounted on said shaft, said thread tensioning device comprising a plurality of co-operating conical rollers, a grooved roller at one end of said series and driven frictionally by the article being wound means actuated by the article being wound as sections of said article become completed for adjusting the position of the thread tensioning device longitudinally 30 of said shaft.

40 4. A thread winding machine including a thread tensioning device comprising a shaft, two relatively movable elements pivoted on said shaft to rock on a common axis, tapered rollers carried by each of said elements, the rollers of one element having a taper opposite to that of the other element, a peripherally-grooved roller carried by one of said elements and frictionally engaging the article being wound, and means operative by the rocking movement of said thread tensioning device incident to the increase in diameter of the article being wound to cause said thread tensioning device to progress along said shaft.

45 5. A thread winding machine including a thread tensioning device comprising two sets of co-operating oppositely tapered rollers past all of which the thread is drawn by the rotation of an article being wound and a 50 roller in frictional engagement with the article being wound and having a peripheral groove through which the thread passes to such article.

55 6. A thread winding machine including a thread tensioning device comprising a pair of members pivotally connected at one end and a series of longitudinally tapered rollers mounted on each member, the taper of the rollers of one member being opposite to that of the rollers of the other member and the movement of the two members toward one another causing the rollers of one member to take up axially parallel positions of the rollers of the other member.

65 7. A thread winding machine including a

thread-tensioning device comprising, a pair of members mounted adjacent one of their ends to swing toward and away from one another and toward and away from an article being wound on an axis parallel to the axis of the latter, a plurality of rollers carried by each of said members past which rollers the thread passes to said article, the rollers of each member being substantially equidistantly spaced apart to receive the members of the other roller therebetween, the roller adjacent the free end of one of said members frictionally engaging said article and having a peripheral groove through which the thread passes on its way to said article.

In testimony whereof I have hereunto set my hand.

NICOLAI GRIBOJEDOFF.
